UNITED STATES PATENT OFFICE.

EUGENE A. RIOTTE, OF BRONXVILLE, NEW YORK, ASSIGNOR TO STANDARD MOTOR CONSTRUCTION COMPANY, OF JERSEY CITY, NEW JERSEY, A CORPORATION OF NEW JERSEY.

CARBURETER.

1,074,574.

Specification of Letters Patent. Patented Sept. 30, 1913.

Application filed January 18, 1912. Serial No. 671,465

To all whom it may concern:

Be it known that I, EUGENE A. RIOTTE, a citizen of the United States, residing at Bronxville, Westchester County, New York, 5 have invented certain new and useful Improvements in Carbureters, of which the following is a full, clear, and exact description:

My invention relates to improvements in carbureters for internal combustion engines, 10 and consists in an improved embodiment of that type of carbureter set forth and claimed in United States Letters Patent No. 1,006,130, dated October 17th, 1911.

The main object of the present embodiment is to simplify and render more compact said construction, and better adapt the same to use on relatively small engines of the internal combustion variety.

In the drawings Figure 1 is a vertical 20 sectional view illustrating the several parts in operative position. Fig. 2 is a horizontal sectional view on the line α — α Fig. 1. Fig. 3 is a development view of one of the details. Fig. 4 is a relatively enlarged 25 detail view.

1 represents the casing of a reservoir arranged to hold liquid fuel, which is admitted through pipe 2.

3 is a valve ordinarily controlled by a 30 float 4, which valve controls the fuel admission duct to maintain said fuel at a proper level within the casing 1.

5—5 represent a plurality of open-ended sprayer tips at the upper ends of pipes which 35 lead down into the fuel casing 1 so that their lower ends will be immersed in the liquid fuel therein.

6 represents a tube connected to the upper 40 end of casing 1 and controlled by a suitable manually controllable throttle valve or damper 7. The pipe 6 constitutes the feed pipe and leads to the motor. The pipe 6 has a series of inlet ports therein directly adjacent to the several sprayer tips 5—5, 45 which, as shown in Fig. 2, are arranged in ring-like series around the pipe 6.

8 is a sleeve slidable within the pipe 6.

9 is a piston connected to sleeve 8.

10 is a cylinder extending below the casing 50 1. The piston 9 is adapted to said cylinder. The lower end of the pipe 8 is closed by said piston, but there is provided a duct 11 leading from the interior of the pipe 8 to the inclosed space 12 within the cylinder 55 and above the piston 9. This duct 11 is

preferably provided with a valve 13, for the purpose of regulation, although in some instances, and assuming that the size of the duct 11 is proper for certain conditions, said valve 13 is unnecessary.

14 is a stop shoulder limiting the descent of the piston 9 and pipe 8.

15—16 are what I may refer to as regulating sleeves, each having openings corresponding to the air openings in the pipe 6, said sleeves being adjustable to vary the size of the inlets in front of the sprayer tips 5. Any suitable means may be provided for holding the sleeves 15—16 in a proper adjusted position, such, for example, as a 70 clamping screw 17, which may pass through horizontal slots in the said sleeves 15—16 and screw into pipe 6, whereby when said screw 17 is loosened, the regulating sleeves 15—16, or either of them, may be adjusted 75 properly, after which the screw 17 may be tightened up to hold the same against displacement. This affords merely one convenient means for varying the size of the inlets in front of the tips 5. In practice, when the size of these inlet passages has been properly fixed for an engine of a certain size, no further adjustment is required. The sleeve 8 constitutes in effect an automatic valve for controlling the number of air admission passages that are open at any given time, and accordingly the number of sprayer tips 5 that are rendered effective, because it is only when such inlet passages are open that fuel will be drawn from the sprayer tips into the carbureting chamber adjacent to and above said tips and within the aforesaid feed pipe.

The sleeve 8 is provided with a series of slots or openings A, B, C, D, E, F, G, H, 95 of different lengths, these being best seen in the development view of Fig. 3. When the engine with which the carbureter is connected is idle, the valve sleeve 8 will descend by gravity to its lowest position, 100 wherein the piston 9 may rest on stop 14, and wherein the great majority of the air inlets are closed. It is preferable, however, to have at least one of said passages partly open, and this may be provided for by increasing the length of the longest slot, as indicated at A. When the engine is started up and a partial vacuum is created within the pipe 6 and sleeve 8, air will be drawn in through the opening A, simultaneously 110

drawing in a suitable proportion of fuel from the tip adjacent thereto so as to form a mixture for starting the engine. The vacuum within the pipe 8 likewise produces, through the passage 11, a corresponding vacuum in the space 12 above the piston 9, which causes the piston 9 to ascend so as to move upwardly the valve sleeve 8, and to progressively open the inlet ports above referred to so as to progressively supply the needed quantity of air, and likewise the additional quantity of fuel necessary to mix with said air to form the proper explosive mixture within the mixing chamber of feed pipe 6. When there is a demand for an increased volume of a mixture, as is the case when the throttle 7 is opened more, the greater vacuum within the carbureting chamber raises the piston 9 and the sleeve 8 to exactly the desired extent to provide said additional mixture. As the throttle 7 is closed and the vacuum within the pipe 6 is lessened, the piston 9 descends, carrying down with it the valve sleeve 8, and correspondingly reducing the amount of air and gas admitted. All changes in the position of the sleeve 8 are effected without materially varying the proportion of fuel relatively to air, assuming, of course, the carbureter is properly adapted or adjusted to the particular engine with which it is associated. In the present instance, the aforesaid adjusting means enables the expert to adjust the carbureter initially to any particular motor, after which the operation is wholly automatic and uniform throughout the full range of the apparatus.

It will be observed that all springs and similar appliances are eliminated, thereby rendering more certain, durable, and positive the action of the apparatus as a whole, and furthermore reducing materially the danger of breakage. By reason of the construction it is apparent that there is comparatively no wear, since friction is practically eliminated, the sleeve 8 sliding lightly upon the inner wall of the tube 6 and the piston 9 likewise sliding lightly upon the wall of the cylinder 10. It is obvious that by this arrangement the instrument is bound to operate gradually, by which I mean without any undesirable abrupt fluctuation, since the piston 9, by reason of being controlled by its own fixed weight in one direction and by a vacuum established through a comparatively small passage in the other direction, moves evenly and with only sufficient speed to maintain an even and gradual operation, as distinguished from a quick abnormal operation.

I have shown on the bottom of the piston a detachable plate 9^a, which may constitute a weight. While the piston itself may be initially designed for any particular engine so that it will have the proper weight

therefor, in which event a separate plate such as 9^a may be omitted, nevertheless it is apparent that the weight of the piston may be modified by providing such a plate and substituting heavier or lighter plates as required, if it should be desirable to adapt any particular carbureter of this design to an engine for which said carbureter was not originally planned. Any suitable means may be provided to cause said sleeve-like throttle 8 to move up and down in such a manner as to keep the openings therein in proper alignment with the fuel supply nozzles controlled thereby.

18 represents a screen or any suitable construction which may overstand and protect the nozzles 5 and air admission openings. While the design of the carbureter is such that no ordinary amount of dust or dirt will produce any injurious effect therein, nevertheless it is extremely desirable to prevent foreign matter from passing through the engine.

It will be observed that in operation the automatic throttle is in effect in free suspension, it being upheld by the tension of air in the carbureting chamber which remains substantially constant. Of course, as a greater volume of mixture is demanded and the throttle is opened to provide such increased volume, there will be a momentary tendency to increase the tension or vacuum which will lift the automatic throttle at a higher level, but inasmuch as the raising of the throttle admits an increased volume of air, the said increased volume will be found to be in such proportion as to supply a sufficient quantity of air to the carbureting chamber to preserve the initial air tension or vacuum, which, as above suggested, remains substantially constant irrespective of the volume of mixture being formed and transferred through the feed pipe.

Since the preferable construction contemplates the utilizing of the weight of the automatic throttle to counteract the lifting tendency of the vacuum, and since a weight is a constant, it follows that there will be the greatest accuracy in the operation of the instrument.

While the piston or dash pot effect above referred to prevents abnormally quick movement of the throttle when the apparatus is subjected to quickly varying loads, it also is of decided advantage when the apparatus is used on automobiles traveling over rough roads where said apparatus will be subjected to heavy vibration, for in such case, it will be found that such vibration will have no perceptible influence on the throttle by reason of the checking action of said piston or dash pot.

20-20 represent two guide-pins fixed on the inner wall of the pipe 6 and projecting into slot A of the throttle 8. These pins

prevent rotary displacement of the throttle as it rises and falls.

What I claim is:

1. In a carbureter, an annular liquid fuel reservoir, a tubular carbureting chamber mounted therein and extending thereabove provided with a plurality of air admission ports opening directly to the atmosphere, a plurality of fuel supply nozzles arranged concentrically about said chamber and placed with their open ends respectively substantially at the centers of the atmospheric sides of said ports.
2. In a carbureter, an annular liquid fuel reservoir, a tubular carbureting chamber mounted therein and extending thereabove provided with a plurality of air admission ports opening directly to the atmosphere, a plurality of fuel supply nozzles arranged concentrically about said chamber and placed with their open ends respectively substantially at the center of the atmospheric sides of said ports, and means for manually symmetrically varying the size of 25 the ports.
3. In a carbureter, an annular liquid fuel reservoir, a tubular carbureting chamber mounted therein and extending thereabove provided with a plurality of air admission 30 ports opening direct to the atmosphere, a plurality of fuel supply nozzles arranged concentrically about said chamber, placed with their open ends respectively substantially at the center of the atmospheric sides of 35 said ports, and means for manually, symmetrically and simultaneously varying the size of the ports.
4. In a carbureter, an annular liquid fuel reservoir, a tubular carbureting chamber 40 mounted therein and extending thereabove provided with a plurality of air admission ports opening directly to the atmosphere, a plurality of fuel supply nozzles arranged concentrically about said chamber and 45 placed with their open ends respectively substantially at the center of the atmospheric sides of said ports, means for manually symmetrically varying the size of said ports, and an automatic throttle for said 50 ports within the carbureting chamber arranged to open and close the ports and also arranged to cut out one or more of the said fuel supply nozzles from or including the same in the draft through said port, and 55 means controllable by variation in pressure in the chamber for moving said throttle.

5. In a carbureter, an annular liquid fuel reservoir, a tubular carbureting chamber mounted therein and extending thereabove provided with a plurality of air admission 60 ports opening directly to the atmosphere, a plurality of fuel supply nozzles arranged concentrically about said chamber and placed with their open ends respectively substantially at the center of the atmos- 65 pheric sides of said ports, means for manually symmetrically varying the size of the ports, an automatically controllable throttle adapted to open and close said ports pro- 70 gressively, a piston carried by said throttle, a concentric depending cylinder for said piston, and a duct connecting the carbureting chamber with the space within said cyl- 75 inder to produce therein a vacuum corre- sponding to the vacuum in the carbureting chamber for the purpose of moving the piston and controlling the position of said throttle.

6. In a carbureter, an annular liquid fuel reservoir, a tubular carbureting chamber 80 mounted therein and extending thereabove provided with a plurality of air admission ports opening directly to the atmosphere, a plurality of fuel supply nozzles arranged concentrically about said chamber and 85 placed with their open ends respectively substantially at the center of the atmos- 90 pheric sides of the ports, means for manually symmetrically varying the size of the ports, a concentric cylinder depending from 95 said fuel reservoir, a sleeve-like throttle movable up and down in said carbureting chamber having a plurality of passages adapted respectively to said air ports and arranged to progressively open and close 100 the same as the throttle ascends and de- scends, said throttle extending into the de- pending cylinder, a piston carried by the bottom of the throttle, a duct leading from said carbureting chamber into said cylinder 105 above the piston to permit of a vacuum therein corresponding to the vacuum in the carbureting chamber to move said piston and thereby said throttle in keeping with the variations in air tension within the car- bureting chamber and thereby expose more or less of said air ports and fuel supply nozzles.
